UNITED STATES PATENT OFFICE.

SIEGFRIED FULD, OF PHILADELPHIA, PENNSYLVANIA.

MATTRESS.

Application filed January 9, 1923. Serial No. 611,558.

To all whom it may concern:

Be it known that I, SIEGFRIED FULD, a citizen of the United States, residing at Philadelphia, in the county of Philadelphia and State of Pennsylvania, have invented 5 certain new and useful Improvements in Mattresses, of which the following is a specification.

My invention relates to mattresses, more particularly to spring mattresses. Heretofore mattresses of this type were made with a layer of cotton between the spring covering and the outside casing. The objection to this construction was that the springs 10 dislodged the layer of cotton and in a short time wore their way through to the outside casing. This condition caused the mattress to lose its shape and made it very uncomfortable to rest on because the springs had 15 no cotton padding.

The object of my invention is to provide a construction which will prevent the springs from wearing through the cotton layer and which will increase the life of the mattress.

This object, and other advantageous ends which will be described hereinafter, I attain in the following manner, reference being had to the accompanying drawings in which—

Figure 1 is a vertical section through a mattress constructed in accordance with my invention,

Figure 2 a fragmentary plan view of Figure 1 drawn on a smaller scale,

Figures 3 and 4 are different forms of mattress casings constructed in accordance with my invention, and

Figure 5 is a view similar to Figure 1 showing the casing in a modified form.

Referring to the drawings, 7 is a mattress which includes coiled springs 8 enclosed by a covering 9 of fabric or other flexible material. Reinforcing rods 10 are inserted in the corners 11 of the covering to keep the 40 springs in position and to provide corner foundations. A quilted casing 12 encloses the covering and is composed of a layer of fibrous material 13, preferably cotton, and a cloth covering 14. The cotton and the cloth are quilted as shown at 15. The quilting may be of any suitable design, such as 45 squares, diamonds, etc. The corners of the

covering 9 are provided with a filler of cotton 16 sewed thereto so that when the casing is applied, the corners of the casing will 55 be puffed as shown at 17. Laps 18 are provided on the edges of cloth covering 14 so as to permit the casing to be stitched together by a thread 19 in any suitable manner. The casing is secured to the spring 60 cover by stitching threads 20 around rods 10.

In Figure 5, I have shown a casing with cloth coverings 21 and 22 on both sides of the layer of cotton 23. The casing is quilted 65 through the coverings and the layer of cotton by threads 24. The laps 25 are stitched together by a thread 26 in any suitable manner. In all other respects the mattress is similar to that shown in Figure 1 70 and similar parts are given corresponding reference characters.

When the mattress is in use, the quilting will keep the cotton in place and prevent the springs from shifting it or working their 75 way through to the cloth covering. This construction increases the life of the mattress.

While I have described my invention as taking a particular form, it will be understood that the various parts of my invention may be changed without departing from the spirit thereof, and hence I do not limit myself to the precise construction set forth, but consider that I am at liberty to make 85 such changes and alterations as fairly come within the scope of the appended claims.

Having thus described my invention, what I claim as new and desire to secure by Letters Patent is—

1. A mattress comprising a core arrangement characterized by being composed of compressible springs arranged within a covering and by having foundation members holding the springs in position; a casing 95 of uniform thickness completely enveloping the core, and filler expansions arranged within the casing in positions to rest over and to be reinforced by, said foundation members, substantially as described.

2. A mattress comprising a core arrangement characterized by being composed of compressible springs arranged within a casing and by having foundation members hold-

ing the springs in position; a casing of uniform thickness completely enveloping the core and including an outer covering, an inner covering and a filler quilted together, the
5 inner covering at points opposite the foundation members being folded upon itself within the casing filler and containing a filler

within such folds to provide filler expansions within the casing in positions to rest over and to be reenforced by, said foundation members, substantially as described. 10

In testimony whereof I have signed my name to this specification.

SIEGFRIED FULD.
